ROTARY SWAGING OR FORGING MACHINES
Samuel Smith, Elmdon, England, assignor to Stevens & Bullivant Limited, Birmingham, England, a company of Great Britain

Filed Oct. 1, 1959, Ser. No. 843,752

5 Claims. (Cl. 78—21)

The present invention has relation to rotary swaging or forging machines more particularly of the type involving a flywheel rotatably driven on a stationary head carrying radially slidable hammer blocks, the present invention having for its object primarily to silence the noise caused by the reciprocation of the hammer blocks when the machine is out of use with the flywheel running.

According to the present invention there is provided a rotary swaging or forging machine of the type hereinbefore referred to wherein plungers incorporating compensating springs are slidably mounted in the head so as to bear on the side walls of the hammer blocks, means being provided to increase or relieve the pressure of the plungers against the side walls of the hammer blocks.

An object of the present invention is to avoid the necessity of "personal" actuation of the pressure varying means and to provide for automatic reduction of the pressure applied by the plunger when the machine is not in use but still is running.

Further according to the present invention there is provided a rotary swaging or forging machine of the type hereinbefore referred to wherein plungers incorporating compression or compensating springs are slidably mounted in the head so as to bear on the side walls of the hammer blocks said machine incorporating at the entrance or work receiving orifice a member which is displaceable by virtue of the work insertion so as to automatically relieve the pressure exerted by the plungers when the machine is in use but restore the pressure when the work is withdrawn for silencing the machine whilst running and not in use.

In order that the invention may be clearly understood and readily carried into practice reference may be had to the accompanying drawing in which the figure illustrates in longitudinal sectional elevation a swaging or forging machine having silencing means with automatic actuation according to the present invention.

In a convenient embodiment of the present invention there is provided a rotary swaging or forging machine of the type comprising a head *a* with a heavy rotating flywheel *b* mounted thereon and driven as, for example, by a motor on a superstructure by belting. The flywheel carries circumferentially spaced rollers *c* which operate radially movable hammer blocks *d* with dies *e* carried by the head *a* whereon the flywheel is mounted.

The present invention, however, is particularly concerned with the silencing of the hammer blocks when the machine is not actually in use and accordingly in the head which carries the flywheel there are provided four or other suitable number of parallel bores *a*¹ normally horizontal, wherein plungers *a*² are accommodated each plunger being of a two part character with the intermediary of a compression or compensating spring *a*³. One extremity of each composite plunger bears upon a hammer block *d* there being four hammer blocks if four plungers are employed. The other extremity of each composite plunger protrudes into a cavity and is engaged by a flange *f*¹ on an axially displaceable tube *f* within the hollow head of the machine and the opposite extremity of this tube is provided with an adjustable flanged nut *f*² engaged by a roller *g*¹ on the upper extremity of a bifurcated lever *g* (normally disposed vertically) which is pivoted at *g*² to a lower part of the machine and which

2

can be acted upon by an air cylinder *g*³. Accordingly with the present apparatus pressure can be brought to bear upon the plungers *a*² so that they in turn bear against the hammer blocks *d* to prevent chattering. The pressure can be readily relieved when the machine is required for swaging or forging.

At the front or work receiving end of the machine there is provided a curved trigger *h* mounted on a transverse pivot *h*¹ the free extremity of which trigger *h* is resiliently maintained across the work receiving aperture by air pressure, hydraulic, electrical, or mechanical means such as a retractile spring *h*². Conveniently a downwardly projecting arm *h*² on the pivot spindle actuates a pneumatic system which is coupled to the air cylinder *g*³ which acts upon the pivotal bifurcated lever *g* which in turn thrusts the axially displaceable tube *f* to actuate the plungers *a*² with their compression or compensating springs *a*³. Conveniently air under pressure may be admitted at *i* so that the movement of *h* returned by the spring *h*³ opens and closes a valve to *i* connected to air cylinder *g*³.

Accordingly in this invention when the work is introduced into the machine which is running and which has the plungers *a*² silencing the hammer blocks *d*, the said trigger *h* is displaced to admit the entrance of this work and this displacement is used to cut off the air supply from the air cylinder *g*³ so that the pressure against the hammer blocks of the plungers with their springs is relieved. When the work is withdrawn the spring *h*³ returns the trigger *h* to its normal position standing at the entrance aperture and this movement is utilized to again actuate the air cylinder for bringing the plungers into their silencing condition that is to say, pressed against the hammer blocks.

35 Although it is advantageous to utilise a pneumatic system between the trigger and the pivotal bifurcated member it will be appreciated that hydraulic, electrical or mechanical means may be used for this purpose.

I claim:

40 1. In a rotary swaging machine having a plurality of radially reciprocating hammer blocks, a damping device for reducing noise created by such machine when running empty, said damping device comprising, in combination, a plurality of plungers, including springs to expand said plungers longitudinally, fluid pressure means acting to press said plungers longitudinally against the sides of said hammer blocks, a lever and push rod transmission mechanism interposed between said fluid pressure means and said plungers, a conduit for supplying fluid under pressure to said fluid pressure means, a valve in said conduit, yieldable means for normally holding said valve closed, and a trigger to be acted upon by work pieces placed in said machine whereby said trigger controls said valve to thereby relieve said hammer blocks from the retarding effect of said damping device while said swaging machine is operating upon work pieces.

2. In a rotary swaging machine having a plurality of radially reciprocating hammer blocks, a damping device for reducing noise created by such machine when running empty, said damping device comprising, in combination, a plurality of plungers, fluid pressure means acting to press said plungers longitudinally against the sides of said hammer blocks, a lever and push rod transmission mechanism interposed between said fluid pressure means and said plungers, a conduit for supplying fluid under pressure to said fluid pressure means, a valve in said conduit, yieldable means for normally holding said valve closed, and a trigger to be acted upon by work pieces placed in said machine whereby said trigger controls said valve to thereby relieve said hammer blocks from the retarding effect of said damping device while said swaging machine is operating upon work pieces.

3. In a rotary swaging machine having a plurality of radially reciprocatory hammer blocks, a damping device for reducing noise created by such machine when running empty, said damping device comprising, in combination, a plurality of plungers, fluid pressure means acting to press said plungers against the sides of said hammer blocks, transmission mechanism interposed between said fluid pressure means and said plungers, a conduit for supplying fluid under pressure to said fluid pressure means, a valve in said conduit, yieldable means for normally holding said valve closed, and a trigger to be acted upon by work pieces placed in said machine whereby said trigger controls said valve to thereby relieve said hammer blocks from the retarding effect of said damping device while said swaging machine is operating upon work pieces.

4. In a rotary swaging machine having a plurality of radially reciprocatory hammer blocks, a damping device for reducing noise created by such machine when running empty, said damping device comprising, in combination, a plurality of plungers, including springs to expand said plungers longitudinally, fluid pressure means acting to press said plungers longitudinally against the sides of said hammer blocks, a lever and push rod, a conduit for supplying fluid under pressure to said fluid pressure means, a valve in said conduit, yieldable means for normally holding said valve closed, and a trigger to be acted upon by work pieces placed in said machine where-

5 by said trigger controls said valve to thereby relieve said hammer blocks from the retarding effect of said damping device while said swaging machine is operating upon work pieces.

5 10 15 20 25 10 15 20 25

5. In a rotary swaging machine having a plurality of radially reciprocatory hammer blocks, a damping device for reducing noise created by such machine when running empty, said damping device comprising, in combination, a plurality of plungers, fluid pressure means acting to press said plungers against the sides of said hammer blocks, a conduit for supplying fluid under pressure to said fluid pressure means, a valve in said conduit, yieldable means for normally holding said valve closed, and a trigger to be acted upon by work pieces placed in said machine whereby said trigger controls said valve to thereby relieve said hammer blocks from the retarding effect of said damping device while said swaging machine is operating upon work pieces.
